MACHINE-SWITCHING TELEPHONE SYSTEM.

1,307,536.

Specification of Letters Patent. Patented June 24, 1919.

Application filed April 12, 1917. Serial No. 161,565.

To all whom it may concern:

Be it known that we, HENRY P. CLAUSEN and CHARLES L. GOODRUM, citizens of the United States, residing at Mount Vernon, in the county of Westchester and State of New York, and at New York, in the county of New York and State of New York, respectively, have invented certain new and useful Improvements in Machine-Switching Telephone Systems, of which the following is a full, clear, concise, and exact description.

This invention relates to machine switching telephone systems, and particularly to those systems wherein a train of automatic switching mechanisms are operated in succession.

The object of the invention is to provide means whereby the switching mechanism, ordinarily adapted to be operated only after another has completed its operation, may be started before such other has reached the final stage of its operation.

The invention is shown herein as applied to a line finder switch and an associated first selector switch, such arrangement being the preferable embodiment of the invention, but not the only arrangement contemplated.

It sometimes happens that in a system where the selector switches are directly set by the calling subscriber that the first series of impulses is sent before the line finder switch has completed its operation, in which case the first selector is wrongly set, not having received the full set of impulses.

This invention aims to overcome such difficulty by means which allow the impulses to reach and affect the first selector switch after the line finder has started, but before it has found the calling line.

Specifically, the invention contemplates the combination with a line finder switch of means for communicating impulses in a telephone line which has started such line finder switch in action to a selector switch associated therewith.

The invention, as illustrated in the drawing, comprises a telephone system including a calling line and a line finder switch diagrammatically shown at the left of the broken line, and a first selector switch, an indicated connector switch, and a called line diagrammatically shown to the right of the broken line.

The line finder switch and first selector

switch, diagrammatically illustrated, may 55 be of the type shown in the patent to Forsberg, No. 1,252,420, granted January 8, 1918.

A clear understanding of the invention may be had from the following description of the operation of a system embodying this 60 invention.

Let it be assumed that the subscriber at substation A removes the receiver from its hook. A circuit is thereupon established from the battery, the left-hand winding of 65 relay LR, left-hand armature and contact of relay CO, upper limb of the telephone line 1, through the apparatus of the substation A, lower limb of the telephone line 2, contact and right-hand armature of relay CO, 70 right-hand winding of relay LR, to ground. Relay LR is energized and by attracting its armature establishes a circuit from ground, right-hand armature and contact of relay LR, the winding of slow-release relay GR, 75 to battery and ground. Current flowing through this circuit energizes the relay GR, which in turn actuates its armatures and establishes a circuit from ground, the outer right-hand armature and contact of relay 80 GR, side-switch wiper W¹, contact and armature of relay PM, to battery and ground. The relay PM upon attracting its armature breaks the circuit just described and upon retracting its armature again establishes the 85 circuit. In this manner the armature is caused to vibrate until the relay PM is permanently energized in a manner to be described.

The actuation of the outer right-hand armature of the relay GR also establishes a circuit from ground, the outer right-hand armature and contact of relay GR, side-switch wiper W² and its first position contact, and the winding of relay 3, to battery 95 and ground. The relay 3 attracts its armature and opens a circuit for the release magnet which will also be described.

The actuation of the relay LR places a ground on the terminal 4 of commutator C, 100 traceable from ground, right-hand armature and contact of relay LR, to terminal 4. The arm 5 being keyed to the shaft of the switch revolves with it until it comes in contact with a grounded terminal 4. At this 105 time the ground on terminal 4 is projected through the arm 5, side switch wipers W³, W⁴ and their first position contacts, the winding

of escape magnet E, the winding of magnet PM, to battery and ground. The magnet PM permanently attracts its armature and the movement of the arm 5 ceases. Magnet 5 E attracts its armature and in the well-known manner moves the side-switch wipers into their second position.

A circuit is now established from ground, right-hand armature and contact of relay 10 LR, terminal 4, arm 5, side-switch wiper W³ and its second position contact, side-switch wiper W⁶ and its first position contact, the left-hand winding of relay LR¹, to battery and ground. Relay LR¹ is energized and at 15 tracts its armature.

A circuit is also established from ground, the outer right-hand armature and contact of relay GR, side-switch wiper W¹ and its second position contact, armature and contact of relay SM, the winding of relay SM, to battery and ground. Relay SM, by breaking its own circuit, sets up a vibratory action, and moves the brushes B¹, B² and B³ step by step over the terminals T¹, T² 25 and T³.

As the brushes B¹, B² and B³ traverse the terminals T¹, T² and T³ a circuit is established from battery, the winding of cut-off relay CO, the terminal T¹ of other lines in 30 the same group, brush B¹, side-switch wiper W⁵ and its second position contact, the winding of relay TR, to ground, but the current flowing thereover is not great enough to cause the energization of either of these 35 relays. When, however, the brush B¹ encounters the terminal T¹ of the calling line then a circuit will be established from ground, battery, the resistance R¹, inner right-hand armature and contact of relay GR, contact 40 and left-hand armature of relay LR, terminal T¹ and thence over the circuit previously traced. The resistance R¹, being somewhat smaller in value than the resistance of the cut-off relay CO, enough current 45 will now flow over this circuit to energize the relay TR.

When the side-switch wiper W⁴ moved into the second position, the circuit from ground, the contact and armature of relay TR, the 50 second position contact of side-switch wiper W⁴, the winding of magnet E, the winding of magnet PM, to battery and ground, was established, whereby these relays were maintained in their energized condition. Upon 55 the energization of the relay TR this circuit is broken at the armature and contact of relay TR and the magnet E becoming deenergized causes the movement of the side-switch wipers into their third position, which results in the opening of the circuit for the 60 magnet SM and the stopping of the brushes B¹, B² and B³ on the terminals of the calling line.

In the third position, a circuit is established from ground, third position contact 65

and side-switch wiper W⁵, brush B¹, terminal T¹, the winding of cut-off relay CO, to battery and ground. Relay CO now becomes sufficiently energized to attract its armatures, whereupon the energizing circuit 70 for the relay LR is broken, and this relay retracts its armatures. In turn, the relay GR is deenergized and it retracts its armatures.

When the side-switch wipers W⁷ and W⁸ 75 move into the third position the calling telephone line is extended to the first selector switch, whereby the relay LR is maintained energized over a new circuit traceable from ground, battery, left-hand winding of relay 80 LR¹, first position contact and side-switch wiper W⁹, the third position contact and side-switch wiper W⁷, the brush B², the terminal T², lower limb of the telephone line 2, the apparatus of the substation A, the upper 85 limb of the telephone line 1, the terminal T³, the brush B³, the side-switch wiper W⁸ and its third position contact, side-switch wiper W¹⁰ and its first position contact, right-hand armature of relay LR¹, to ground. The energization of relay LR¹ causes the energization of the first slow relay FS over a circuit traceable from ground, the armature and alternate contact of the relay LR¹, winding of 90 relay FS, to battery and ground. The first 95 selector switch is now in condition to receive impulses caused by the intermittent breaking of the line circuit by the actuation of the sender D.

Assuming that the subscriber now actuates this sender, the relay LR¹ will cause its armature to vibrate in the well-known manner. Upon the first retraction of its armature a circuit is established from ground, the armature and normal contact of relay LR¹, 105 the armature and alternate contact of relay FS, to a point where the circuit divides, extending in one direction through the winding of the second slow relay SS, to battery and ground, and in the other direction 110 through the side-switch wiper W¹¹ and its first position contact, the winding of primary magnet PM¹, to battery and ground. Upon the attraction of its armature by the relay LR¹ the magnet PM becomes deenergized but the relay SS, being slow to release does not retract its armature for an appreciable time thereafter. If there be more than one break in the line caused by the 115 operation of the sender D, then the magnet PM¹ will be energized in synchronism with each such break and the brushes B⁴, B⁵ and B⁶ will be rotated in position before the group containing the terminals T⁴, T⁵ and T⁶. 120

The energization of the second slow relay SS results in the establishment of a circuit from ground, the armature and contact of relay SS, the winding of magnet E¹ to battery and ground. At the end of the first 130

series of impulses, the relay SS is given time to deenergize, and upon retracting its armature breaks the circuit for the energization of magnet E^1 and allows the side-switch wipers of this first selector switch to be moved into their second position. As the side-switch wiper W^{12} moves into its second position, a circuit is established from ground, armature and alternate contact of relay LR^1 , the side-switch wiper W^{12} and its second position contact, the armature and contact of relay SM^1 , to battery and ground. The relay SM^1 by attracting its armature opens this circuit and thereby causes a vibratory action which drives the brushes B^4 , B^5 and B^6 over the terminals T^4 , T^5 and T^6 until the brush B^4 encounters the terminal T^4 of an idle trunk, which is characterized in the well-known manner by a ground potential. Thereupon ground will be projected from the terminal T^4 over the brush B^4 , the second position contact and side-switch wiper W^{13} , the winding of magnet E^1 , to battery and ground, and the magnet E^1 will be energized, thereby escaping the side switch wipers into their third position.

The movement of the side-switch wipers W^9 and W^{10} into their third position results in the seizure of the trunk leading to the connector switch CS, whereupon the ground projected to the terminal T^4 is removed and the trunk characterized, by the absence of this ground, as busy.

In the well-known manner, the connector switch CS is driven into association with the line leading to the subscriber B, and other operations necessary to the establishment of the connection performed.

Assuming that the called subscriber answers and that after a period of conversation he replaces the receiver on its hook. This action results in the placing of ground on terminal T^4 , whereupon such ground is projected over the brush B^4 , through the side-switch wiper W^{14} and its third position contact to a point where the circuit divides, extending in one direction through the off-normal contact ON^1 , the winding of the release magnet R^2 , to battery and ground, and in the other direction through the armature and contact of relay 3, which became deenergized when the side-switch wiper W^2 moved into the third position, the off-normal contact ON , the winding of release magnet R, to battery and ground. Both of these release magnets attract their armatures and establish holding circuits for themselves from ground, the contact and armature of relay R^2 , in the one case, and ground, the contact and armature of relay R in the other case. These relays are then held energized until the respective switches are fully released, whereupon the opening of the off-normal contacts breaks their holding circuits.

Assume that the line finder switch has reached the stage in its operation where the arm 5 has made contact with the terminal, and the side-switch wipers W^3 and W^4 have been moved into their second position. Assume also that the subscriber at substation A manipulates his dial switch an instant later. During the following movement of the shaft, in response to the actuation of the secondary magnet, the arm 5 remains in contact with the terminal 4, being keyed to the shaft for this purpose. The relay LR^1 which has just been energized over the circuit previously traced through the second position contact and side-switch wiper W^3 , etc., will now be deenergized through the retraction of its armatures by the relay LR , directly controlled by the subscriber's substation apparatus. The impulses sent will cause the armature of relay LR to vibrate and such vibration will be communicated over the circuit previously traced, and in the manner previously described, to the relay LR^1 , causing it to vibrate its armature in synchronism. The action described in connection with the first selector switch will now take place exactly as before with the exception that the energization of the relay LR^1 is caused by a circuit extending through its left-hand winding only. If, before the train of impulses being sent by the subscriber is completed, the line finder switch completes its operation and the cut-off relay CO is thereby energized, the side-switch wipers W^7 and W^8 will extend the calling line to the relay LR^1 , and it will continue in its vibration now under control of the circuit through which both its right and left-hand windings are energized. The action thereafter is as previously described.

What is claimed is:

1. In a telephone system, a telephone line, a two-movement non-numerical switching mechanism, a numerical switching mechanism, and means included in said non-numerical mechanism operable upon the completion of its first movement for bringing said numerical switching mechanism under the control of said line.

2. In a telephone system, telephone lines, automatic switching mechanisms for extending said telephone lines, directly controlled switching mechanisms for further extending said telephone lines, means included in said automatic switching mechanisms operable before said automatic switching mechanisms have completed their selecting operation for bringing said directly controlled switching mechanisms under the control of said telephone lines.

3. In a telephone system, telephone lines, switching mechanisms arranged to be directly controlled by said telephone lines, automatic switching mechanisms for extend-

ing said telephone lines to said directively controlled switching mechanisms, and means included in said automatic switching mechanisms operable before said automatic switching mechanisms have completed their selecting operation for bringing said directively controlled switching mechanisms under control of said lines.

4. In a telephone system, a non-numerical switching mechanism, a numerical switching mechanism, and means included in said non-numerical switching mechanism for starting said numerical switching mechanism prior to the completion of the selecting operation of said non-numerical switching mechanism.

5. In a telephone system, a non-numerical selector, a numerical switching mechanism, and means included in said non-numerical selector operable before said non-numerical selector has completed its selecting operation for starting said numerical switching mechanism.

6. In a telephone system, selector switches arranged for successive operation, and means included in one for actuating another before the one has completed its selecting operation.

7. In a telephone system, telephone lines, selector switches, means including said selector switches for interconnecting said lines, said switches being arranged for successive operation, and means included in the first of said switches to be actuated for starting the second of said switches before the said first of said switches has completed its function.

8. In a telephone system, a two-movement non-numerical switching mechanism, a numerical switching mechanism, and means included in said non-numerical mechanism,

operable upon the completion of its first movement for starting said numerical switching mechanism.

9. In a telephone system, a telephone line, 45 a non-numerical switching mechanism for extending said line, a numerical switching mechanism for further extending said line, and means included in said non-numerical switching mechanism for bringing said 50 numerical switching mechanism under control of said line before said non-numerical switching mechanism has extended said line to said numerical switching mechanism.

10. In a telephone system, a telephone 55 line, a non-numerical selector, a numerical selector, and means included in said non-numerical selector operable before said non-numerical selector has completed its selecting operation for placing said numerical 60 selector under the control of said line.

11. In a telephone system, a telephone line, selector switches arranged for successive operation, and means included in one for bringing the other under the control of 65 said line before the one has completed its selecting operation.

12. In a telephone system, telephone lines, selector switches, means including said selecting switches for interconnecting 70 said lines, said switches being arranged for successive operation, and means included in the first of said switches to be actuated for bringing the second of said switches under the control of said lines, before the 75 said first of said switches has completed its function.

In witness whereof we hereunto subscribe our names this 11th day of April, A. D., 1917.

HENRY P. CLAUSEN.
CHARLES L. GOODRUM.
